DESIGN FOR A LIGHT PROJECTING FIXTURE OR SIMILAR ARTICLE

Jo Mielziner, New York, N. Y., assignor to Century Lighting, Inc., a corporation of New York

Application November 16, 1939, Serial No. 88,320

Term of patent 14 years

To all whom it may concern:

Be it known that Jo Mielziner, a citizen of the United States and resident of New York city, in the county of New York and State of New York, has invented a new, original, and ornamental Design for a Light Projecting Fixture or Similar Article, of which the following is a specification, reference being had to the accompanying drawing, forming part thereof, in which Fig. 1 is a perspective view of a light projecting fixture em-

bodying the new design; Fig. 2 is a rear elevational view thereof; and Figs. 3 and 4 are side elevational views showing the fixture in position for projecting the light in the angular direction downward and in a vertical upward position, respectively.

I claim:

The ornamental design for a light projecting fixture or similar article, as shown.

JO MIELZINER.
